FOREIGN PATENT DOCUMENTS

WO D235312-001 * 3/2024

Primary Examiner — S. Bryan Reinholdt, Jr.

(57) **CLAIM**

The ornamental design for a bottle rack for storage as shown and described.

DESCRIPTION

1.1 is a front perspective view of a bottle rack for storage showing a first embodiment of my new design;

1.2 is a rear view thereof;

1.3 is a bottom view thereof;

1.4 is a front view thereof;

1.5 is a right side view thereof;

1.6 is a left side view thereof;

1.7 is a top view thereof;

2.1 is a front perspective view of a bottle rack for storage showing a second embodiment of my new design;

2.2 is a rear view thereof;

2.3 is a bottom view thereof;

2.4 is a front view thereof;

2.5 is a right side view thereof;

2.6 is a left side view thereof; and

2.7 is a top view thereof.

The broken lines and the areas within them depict portions of the bottle rack for storage that form no part of the claimed design.

1 Claim, 14 Drawing Sheets
